(57) **CLAIM**

The ornamental design of a fetal monitor, as shown and described.

DESCRIPTION

FIG. 1 is a front elevational view of a fetal monitor, showing my new design;

FIG. 2 is a side elevational view thereof;

FIG. 3 is a top plan view thereof; and,

FIG. 4 is a top perspective view thereof.

The surfaces not shown of the fetal monitor form no part of the claimed design.

The broken line showing is for illustrative purposes only and forms no part of the claimed design.
